UNITED STATES PATENT OFFICE.

REUBEN JOHN LINES, OF NORTHAMPTON, ENGLAND.

WOOD-CUTTING MACHINE.

SPECIFICATION forming part of Letters Patent No. 783,877, dated February 28, 1905.

Application filed August 23, 1904. Serial No. 221,813.

To all whom it may concern:

Be it known that I, REUBEN JOHN LINES, a subject of the King of Great Britain, residing at Northampton, England, have invented certain new and useful Improvements in Wood-Cutting Machines, of which the following is a specification, such as will enable those skilled in the art to which it appertains to make and use the same.

10 This invention relates to machines for cutting wood; and the object thereof is to provide an improved machine of this class which is designed for use in cutting wood for various purposes, such as the making of various kinds 15 and classes of furniture and for making boxes of various shapes or forms, a further object being to provide a machine of the class specified which is particularly designed for cutting wood, boards, or lumber at any desired angle 20 and for making miter-frames, picture-frames, and for various other purpose.

The invention is fully disclosed in the following specification, of which the accompanying drawings form a part, in which the separate parts of my improvement are designated by suitable reference characters in each of the views, in which —

Figure 1 is a plan view of my improved wood-cutting machine; Fig. 2, a front view 30 thereof, partially in section; Fig. 3, a back view, partially in section; Fig. 4, a left-hand side elevation; Fig. 5, a section on the line 55 of Fig. 2; Fig. 6, an inside view of an adjustable bearing-block, one of which is employed at each end of the machine; and Fig. 7, an outside view of a rotatable disk, one of 35 which is employed at each end of the machine and used in connection with the bearing-blocks, one of which is shown in Fig. 6, said disk or disks being employed for the purpose 40 of tilting the cutting tool or tools.

In the practice of my invention I provide a rigid main frame comprising side plates or members a , connected at the back by a bar a^2 45 and in the bottom rear portion by a bar a^3 , these parts being clearly shown in Figs. 1, 2, 3, 4, and 5. Each of the side plates a is provided in the rear top portion thereof with an angular recess b , the outlines of which are 50 formed by the lines b^2 and b^3 , b^3 and b^4 , and b^4

and b^5 , as clearly shown in full lines in Fig. 5 and in dotted lines in Fig. 4, and each of the side plates or members a is provided with a bearing-box c , an inside view of one of which is given in Fig. 6, and these bearing-boxes are 55 connected with the outside thereof so as to cover the recesses b , this connection being made by means of bolts c^2 , which pass through said bearing-boxes and through the side plates or members a , and the holes c^3 in the bearing-boxes c , through which the bolts c^2 pass, are made oblong, so as to permit of the slight forward and backward adjustment of said bearing-boxes, and each of said bearing-boxes is provided at its front end with a screw c^4 , which 60 is rigidly connected therewith, and the screws c^4 pass through keepers c^5 , formed on or connected with the side plates or members a of the main frame, and the screws c^4 are provided at the opposite side of the keepers c^5 with set-nuts c^6 , and by means of this construction the bearing-boxes c may be adjusted within certain limits forwardly and backwardly of the main frame. The bearing-boxes c are also provided centrally thereof with a vertically-arranged oblong and rectangular opening c^7 75 and in the inner side thereof with segmental grooves c^8 , three of which are shown, and these grooves c^8 open upwardly, and said bearing-boxes are also provided in their upper 80 edge and midway thereof with a V-shaped recess c^9 .

In the bearing-boxes c and held therein by the side plates or members of the main frame are placed rotatable disks d , an inside view of one of which is given in Fig. 7, and these disks d are provided with concentrically-arranged ribs d^2 , which fit in the grooves c^8 in the bearing-boxes c , and said disks are each provided in the bottom half thereof with a segmental 90 opening d^3 and in the top thereof with a vertically-arranged oblong rectangular opening d^4 , provided with a backwardly-directed angular recess d^5 , and said disks d are also provided rearwardly of the opening d^4 with screw 95 or bolt holes d^6 .

The main frame is provided with a table a^4 , which forms a part of the main frame and which extends backwardly to the recess b in the side plates or members a of the main 100

frame, and when the bearing-boxes *c* are in position they extend to the top of the table *a*⁴, as shown in Figs. 2 and 4, and the diameter of the rotatable disks *d* is substantially twice that of the vertical width of the bearing-boxes *c*, and said rotatable disks extend a distance above the table *a*⁴ equal approximately to one-half of their diameters.

The rotatable disks *d* are rigidly connected by a horizontally and vertically arranged plate *e*, having angular end members *e*², which are bolted or secured to said disks by means of bolts or screws *e*³, which pass through said angular end members *e*² of the plate *e* and through the holes *d*⁶ in the disks *d*, and the front side or surface of said plate *e* is flush with the rear walls of the openings *d*⁷ in said disks, and said plate *e* is provided in the front top portion thereof with a longitudinal groove *e*⁴ and in the bottom portion thereof with a longitudinal slot *e*⁵.

Mounted centrally on the plate *e* is an angular keeper *f*, which is secured thereto by bolts or screws *f*² and which extends a predetermined distance in front of said plate, and mounted on the keeper *f* is another angular keeper *g*, which extends backwardly of the plate *e* and is provided with a depending member *g*² and with inwardly-set end ears *g*³, by which it is bolted to the plate *e*, this construction being clearly shown in Figs. 1, 2, 3, and 4, and the keeper *g* is provided with an upwardly-directed hub or bearing *g*⁴, in which is mounted a vertically-arranged spindle *g*⁵, the upper end of which is angular in form, as shown at *g*⁶, and adapted to receive a crank or other operating device and the lower end of which is provided with a gear or pinion *g*⁷, and the plate *e* is cut out in the top thereof, as shown at *e*⁶ in Fig. 5, to receive the pinion or gear *g*⁷. Mounted in front of the plate *e* and passing through the keeper *f* is a rack-bar *h*, which is adapted to be operated by the pinion or gear *g*⁷, and the bottom of said bar is provided with a downwardly-directed member *h*², to which the cutting-blades *h*³ are secured, said blades being secured to said member by bolts or screws *h*⁴. The opposite ends of the member *h*² converge downwardly from the rack-bar *h* and range at an angle of about forty-five degrees thereto, and the edges *h*⁵ of the cutting-blades *h* converge at a similar angle.

Mounted in the longitudinal slot *e*⁵ in the plate *e* is a slide *i*, to which the downwardly-directed member *h*² of the rack-bar *h* is bolted, as shown at *i*² in Figs. 3, 4, and 5, and the slide *i* is provided at the back of the plate *e* with downwardly and upwardly directed flanges *i*³, and by this means the rack-bar and the member *h*² thereof, to which the cutting-blades *h*³ are secured, is firmly held in place and at the same time free to move longitudinally of the plate *e*, and the bottom screws or bolts, which hold the cutting-blades *h*³ in posi-

tion, or the ends thereof, also enter and move in the longitudinal slot *e*⁵ in the plate *e*, while the top screws or bolts, used for holding the said cutting-blades in position, or the rear ends thereof, fit and move in the longitudinal groove *e*⁴ in the plate *e*.

In the bottom portion of the main frame and arranged centrally of the bearing-boxes *c*, is a horizontal shaft *j*, composed of two parts *j*², and the opposite ends of which are provided with reversed threads, as shown at *j*³, and the ends of this shaft pass through segmental blocks *j*⁴, mounted in the segmental recesses *d*³ in the rotatable disks *d*, and which serve to limit the movement of said disks, and the ends of said shaft also pass through nuts *j*⁵, which fit in the rectangular openings *e*⁷ in the bearing-boxes *c*, and one end of said shaft is provided with a crank *j*⁶, and the ends of said shaft on the inner sides of the side plates *a* or members *a* of the main frame are also provided, in the form of construction shown, with locking-nuts *j*⁷, which may or may not be employed. The separate parts of the shaft *j* are connected centrally thereof by a sleeve *j*⁸ in the form of construction shown; but this connection may be made in any desired manner, and the object of the shaft *j* is to provide means for holding the rotatable disks *d* in proper position and in contact with the side plates or members *a* of the main frame, and also to provide means for limiting the rotation of said disks in either direction.

I have also shown at *k* a work-piece, or a board which it is designed to cut, and this board is placed on the table *a*⁴ at one side of the machine, and the rear edge thereof is moved backwardly to the rear edge of said table, and in practice the spindle *g*⁵ is turned by the crank *k*² or in any desired manner, and this operation moves the rack-bar *h* in the desired direction or toward the board *k*, according to the direction in which the spindle *g*⁵ is turned, and the rear edge or side of the board *k* will be cut off by the blade or blades *h*³, and the angle of the cut will depend on the position of the plate *e*. It will be understood that the plate *e*, which carries the rack-bar *h* and blades *h*³, may be turned forwardly or backwardly within certain limits to any desired angle, and this will not interfere with the operation of the rack-bar *h* and the blades *h*³, and the edge or side of the board *k* may be cut off at any desired angle within certain limits, and when the said plate *e* and rack-bar *h* are swung backwardly the angular members *e*² at the end of the plate *e* move in the recesses *b* in the end plates or members *a* of the main frame, and the recesses *e*⁹ in the top portions of the bearing-boxes *c* are intended to permit of the passage of the bottom portion of the member *h*², which carries the cutter-blades *h*³, and also the bottom portions of said cutter-blades, it being understood that the rack-bar *h*, together with the cutter-blades *h*³, may be projected

beyond either side of the machine in the operation thereof, and in Fig. 3 said parts are shown projected to the left. It will also be understood that the work-piece *k* may be 5 placed at either side of the machine, and in practice is usually placed at one side and then at the other, and it will also be understood that the plate *e* may be held at any desired angle for any necessary time, and the machine 10 may be operated by one man, who holds the work-piece *k* with one hand and holds the crank which operates the spindle *g* with the other hand.

Constructed as hereinbefore described, it 15 will be seen that the leading features of my improved wood-cutting machine consist of a main frame having a front table vertically arranged and rotatable disks mounted at the ends of the main frame and connected by a 20 horizontally and vertically arranged plate forming a support for the rack-bar, a rack-bar mounted in said support and provided with depending cutter-blades, and means for operating said rack-bar and other means for 25 holding the rotatable disks at any desired point.

My invention is not limited to the exact details of the construction herein shown and described, as many changes therein and modifications thereof may be made without departing 30 from the spirit of my invention or sacrificing its advantages, and I reserve the right to make all such alterations therein as fairly come within the scope of the invention.

35 Having fully described my invention, what I claim as new, and desire to secure by Letters Patent, is—

1. In a wood-cutting machine, a main frame provided with a front horizontal table, the vertically-arranged rotatable disks mounted in the ends of the main frame and connected by 40 horizontally and vertically arranged support at the rear of the table, a rack-bar connected with said support and movable longitudinally thereof and through said disks and provided with depending cutter-blades the edges of 45 which converge, and means for operating said rack-bar and for turning the support and disks forwardly and backwardly; substantially as 50 shown and described.

2. In a wood-cutting machine, a main frame provided with a front horizontal table, the vertically-arranged rotatable disks mounted in the ends of the main frame and connected by 55 a horizontally and vertically arranged support at the rear of the table, a rack-bar connected with said support and movable longitudinally thereof and through said disks and provided with depending cutter-blades the edges of 60 which converge, and means for operating said rack-bar and for turning the support and disks forwardly and backwardly, and devices for limiting the movement of said disks in the main frame, substantially as shown and described.

3. In a wood-cutting machine, a main frame 65 provided with a front horizontal table, rotatable disks mounted in the ends of said frame and connected by a horizontally and vertically arranged support, a rack-bar mounted in said support and movable longitudinally thereof 70 and provided with depending cutter-blades, and a spindle mounted vertically in said support and provided with a pinion or gear operating in connection with said rack-bar, and means whereby said disks may be held at any 75 desired point of rotation, substantially as shown and described.

4. In a wood-cutting machine, a main frame provided with a front horizontal table, bearing-boxes secured to the ends of the main 80 frame, vertically-arranged and rotatable disks mounted between said boxes and the ends of the main frame and connected by a horizontally and vertically arranged support, said support being above said table, a rack-bar connected with said support and movable longitudinally thereof and provided with depending cutter-blades, and means for operating said 85 rack-bar, substantially as shown and described.

5. In a wood-cutting machine, a main frame 90 provided with a front horizontal table, bearing-boxes secured to the ends of the main frame, vertically-arranged and rotatable disks mounted between said boxes and the ends of the main frame and connected by a horizontally and vertically arranged support, said support being above said table, a rack-bar connected with said support and movable longitudinally thereof and provided with depending cutter-blades, and means for operating said 95 rack-bar, consisting of a vertically-arranged spindle mounted in said support and provided with a pinion or gear operating in connection therewith, substantially as shown and described. 100

6. In a wood-cutting machine, a main frame provided with a front horizontal table, bearing-boxes secured to the ends of the main frame below the table, vertically-arranged and rotatable disks mounted in said boxes and projecting above the table and connected by a horizontally and vertically arranged support, a rack-bar connected with said support and movable longitudinally thereof and through 105 said disks and provided with depending and converging cutter-blades, and means for operating said rack-bar and for turning the support and the disks forwardly and backwardly, substantially as shown and described.

In testimony that I claim the foregoing as 110 my invention I have signed my name, in presence of the subscribing witnesses, this 9th day of August, 1904.

REUBEN JOHN LINES.
